UNITED STATES PATENT OFFICE.

ROSCOE MARANZINO, OF LOS ANGELES, CALIFORNIA.

ILLUMINATED RADIATOR CAP.

Application filed January 29, 1927. Serial No. 164,578.

This invention relates to radiator caps for automobiles.

The general object of this invention is to provide an ornamental radiator cap which 5 may be electrically illuminated.

Another object of this invention is to provide an electrically illuminated ornamental radiator cap which will not interfere with the filling of the said radiator.

10 Still another object of the invention is to provide a simple and effective means for supplying electric current to an ornamental radiator cap.

Other objects and advantages of which 15 invention will be apparent from the following description taken in connection with the accompanying drawing wherein:

Fig. 1 is an exterior view of my device.

Fig. 2 is a vertical section through my device showing the various parts thereof assembled.

Fig. 3 is a section taken on line 3—3 of Fig. 2.

Fig. 4 is a side elevation of the lamp 25 holder.

Fig. 5 is a top plan view of the contact rings used in conjunction with my device, and

Fig. 6 is an elevation of an automobile 30 having my ornamental radiator cap applied to the radiator spout.

Referring to the drawings by reference characters I have indicated my device at 10 as applied to the filling neck 11 of the radiator 12 of an automobile 13. The radiator 12 is of the usual type and is provided with an overflow pipe 14.

As shown the radiator neck 11 has an enlarged upper portion 15 which is provided 40 with screw threads 16. At the juncture of the neck 11 and the enlarged upper portion 15 a shoulder 17 is formed.

My device consists of two units, a cap 18 and a contact ring 19. The cap 18 takes the 45 place of the usual radiator cap and is composed of three parts, a central ring 20, a lamp base 21, and a cover member 22.

The ring 20 is made of metal and includes 50 an internal flange 23 having at its outer periphery an upstanding circular flange 24. The flange 24 is provided on its inner and outer surfaces with screw threads. The flange 23 is provided with a central threaded aperture 25.

55 The lamp base 21 is preferably made of high heat insulating material and includes

a bottom portion 26, an intermediate boss 27, and a threaded upper portion 28. The boss 27 takes the form of a truncated cone and has a beveled under portion 29 and a top 60 shoulder 30. The lamp base is also provided with a central cylindrical aperture 31 closed at its lower end and opened at its upper end. Mounted in the lower portion 26 of the lamp base 21 I have shown a pair of lamp 65 electrical contact members 32 and 33 having portions 34 and 35 extending up into the central vertical aperture 31.

For conveying electric current to the contact members 32 and 33 I show metal strips 70 36 and 37 molded in the lower portion 26 and the flange 27 and connected to the contact members 32 and 33. The strips 36 and 37 have resilient contact portions 38 and 39 protruding out from the beveled portion 29. 75

Arranged in the lower portion of the base 21 I show screw threaded bushings 40 which are adapted to receive set screws 41 (see Fig. 3) to hold the lamp L in place.

The cover member 22 is made of metal and is shown as comprising an upper dome shaped portion 42, a lower externally threaded flange 43, and a knurled straight intermediate portion 44. Arranged around the sides 80 of the conical portion 42 in staggered formation I have shown a plurality of apertures 45 in which are pieces 46 which may be in the nature of colored glass jewels. On the top of the conical portion 42 I also provide an aperture 47 similar to the apertures 45, 90 only larger, in which I also arrange a glass jewel 48.

The jewels 46 and 48 are preferably secured in position by a suitable cement and are preferably arranged to produce a pleasing effect by the use of various colors. 95

To assemble the radiator cap 18 as shown in the drawings the threaded portion 28 of the lamp base 21 is screwed into the threaded central bore 25 of the central ring 20 and then the double contact electric light bulb L is placed in the central vertical aperture 31 of the lamp base 21 and is so positioned that its contacts engage the contact members 34 and 35 of the lamp base. The electric light bulb L is held in position by clamping the base of the same in a rigid position by means of the set screws 41 in the lower portion 26 of the lamp base 21 (see Fig. 3). After the light L has been placed 100 in position the cover member 22 is secured to the central ring 20 by means of the exten- 105 sions 43 and 44 of the cover member 22. 110

nal threads of flange 43 engaging the internal threads of flange 24 of ring 20. This assembly of the ring 20, lamp base 21 and cover 22 forms the unit previously mentioned as the radiator cap 18.

The contact ring 19 comprises a circular ring 49 and a segmental member 50 made of a high heat and electrical insulating material (see Fig. 5) set in a cut-away portion 51 of ring 49. As shown in Fig. 5 the insulated ring 50 extends less than half way around the metal ring 49, the purpose of this will be more fully described hereinafter.

For securing the insulated segment 50 to the metal ring 49 I have shown set screws 52 engaging threaded apertures in the ring 49 and threaded inserts 53 in the insulated ring 50. The inserts 53 are preferably molded in the insulated ring 50.

20 The contact ring 19 which includes the combination of the metal ring 49 and the insulated segment 50, is provided with a central conical aperture 54, the sides of which are beveled as at 53 to correspond to the bevel 29 on flange 27 of the lamp base 21.

The insulated ring 50 is provided on its beveled portion with a metal contact segment 56 which terminates short of the ends 30 of the segment 50 and which is preferably held in position by molding in the segment 50 tongues 57 of the contact ring 56. The contact ring 56 is provided on the under side of the insulated segment 50 with a terminal 58. On the under side of the metal ring 49 I provide a plurality of spurs 59, the function of which will be more fully described hereinafter.

40 To install my device on an automobile the contact ring 19 is placed in the enlarged upper portion 15 of the radiator neck 11 so that it rests on the shoulder 17, and the spurs 59 are forced into the metal of said shoulder to prevent the contact ring from turning, a wire W having previously been secured to the terminal 58 and preferably run through the overflow pipe 14 to a switch (not shown) on the instrument board of the automobile. After the contact ring 19 has 45 been placed in position the cap unit 18 which includes the central ring 20, lamp base 21 and ornamental cover 22, is attached to the neck 11 by the external threads of the flange 24 of the central ring 20 engaging the 50 internal threads 16 of the enlarged neck portion 15.

When the cap 18 has been secured in position the contact portions 38 and 39 on the bevel 29 of flange 27 of the lamp base 21 will rest on the beveled portion 55 of contact ring 19 and one of said contacts will engage the contact ring 56 of the insulated portion 50, while the other contact will engage the metal ring 49. As shown in Fig. 2 the contact portion 38 engages the contact segment 56

and the contact portion 39 engages the metal ring 49 of contact ring 19.

When the contacts 38 and 39 are thus positioned the electric current will, when the switch is turned on, flow from the wire W, 70 through the terminal 58 into the contact segment 56, whence it will pass into the contact portion 38 and through the strip 36 to the contact 32. From the contact 32 the current will pass through the electric lamp L, 75 and into the contact 33, whence it will pass through the strip 37 to the contact portion 39. From the contact portion 39 it will pass through the metal portion 49 of contact ring 19 to the radiator neck 11 and thence back 80 through the vehicle body to the battery, whence it originated.

By extending the contact ring 56 of the insulated member 50, less than half way around the contact ring 19, I prevent any 85 possibility of ever having both the contact portions 38 and 39 of the lamp base engage the contact ring 56 at the same time, thus causing a "short".

To fill the radiator 12 with water it is only 90 necessary to remove the cap unit 18, the contact ring 19 need not be disturbed as the water may be poured into the neck 11 through the aperture 54 in said ring.

From the foregoing description it will be 95 apparent that I have provided a novel and efficient ornamental radiator cap for automobiles which can be economically manufactured and quickly installed.

What I claim is:

1. In combination with an automobile provided with a radiator and having a filling spout, a ring in said spout, a cap for said filling spout, said cap having transparent members therein, an electric lamp in said 105 cap, contacts in said cap and connected to said electric lamp, said ring being provided with electrical contacting means, the contacts on said cap being arranged to engage the contacting means of said ring to conduct 110 current to said lamp.

2. In combination with an automobile radiator having a threaded filling spout thereon, a cap for said spout, said cap having threads to engage the threads of said 115 spout, an electric lamp base in said cap, an aperture in said cap, an electric lamp in said base, apertures in the walls of said cap, transparent members fitted in said apertures, a contact ring in said radiator spout, said contact ring including means for receiving electric current and means for grounding said electric current, said receiving means and said grounding means being insulated from each other, means in said lamp base for conducting current from said receiving means to said lamp and means for conducting current from said lamp to said grounding means, said contact ring being so constructed that at no time will both of said 130

current conducting means contact with said receiving means.

3. In combination with a threaded spout a cap, said cap comprising an intermediate portion, a base, and a cover, said intermediate portion comprising a ring having an inwardly directed circular flange, said ring having external threads, said flange having internal threads, said lamp base comprising a lower portion, an intermediate circular boss and an upper portion and having an aperture therein, said boss being beveled from its outer periphery downward and inward to said lower portion, said upper portion having screw threads on its outer periphery engaged with the threads on said flange, a pair of contacts at the bottom of said lamp base, and a pair of oppositely disposed contacts on the beveled surface of said flange, means for connecting each of said contacts on said beveled surface with one of said contacts on the bottom of said base, said cover comprising a hollow upper portion and a reduced lower circular flange, said lower flange engaging said ring, said upper portion being provided with apertures therethrough, transparent members secured in said apertures, and means to connect the contacts in said flange with a source of electricity.
- 30 4. In an article of manufacture, a cap, said cap comprising an intermediate portion,

a base, and a cover, said intermediate portion comprising a ring having an inwardly directed circular flange, said ring having external threads, said flange having internal threads, said lamp base being constructed of insulating material and comprising a lower portion, an intermediate circular boss and an upper portion and having an aperture extending from the top surface of said upper portion to a point adjacent the lower end of said lower portion, said boss being beveled from its outer periphery downward and inward to said lower portion, said upper portion having screw threads on its outer periphery engaged with the threads on said flange, a pair of contacts at the bottom of said lamp base, and a pair of oppositely disposed contacts on the beveled surface of said flange, means for connecting each 35 of said contacts on said beveled surface with one of said contacts on the bottom of said base, said cover comprising a hollow upper portion and a reduced lower circular flange, said lower flange engaging said ring, said 40 upper portion being provided with apertures therethrough, and transparent members secured in said apertures.

In testimony whereof, I hereunto affix my signature.

ROSCOE MARANZINO.
